UNITED STATES PATENT OFFICE

RUDOLPH VUILLEUMIER, OF NEW ROCHELLE, NEW YORK, ASSIGNOR TO THE SAFETY CAR HEATING & LIGHTING CO., A CORPORATION OF NEW JERSEY.

METHOD AND APPARATUS FOR SEPARATING LIQUID GASES.

Application filed November 3, 1916. Serial No. 129,271.

To all whom it may concern:

Be it known that I, RUDOLPH VUILLEUMIER, a citizen of the United States, and a resident of New Rochelle, in the county of Westchester and State of New York, have invented an Improvement in Methods and Apparatus for Separating Liquid Gases, of which the following is a specification.

This invention relates to the separation of liquefied gases, and with regard to certain more specific features, to apparatus and method for separating liquefied gases by rectification.

One of the objects of the present invention is to provide a compact apparatus and method wherein the steps or stages are so arranged as to minimize the external losses, which in the case of low-temperature work take the form of so-called heat gains.

Another object is to provide simple and reliable apparatus for facilitating the transfer of heat from one fluid to another and for accelerating the separation of the several constituents of the fluid.

Another object is to provide a method of the above general type in which there is an effective interchange of latent heat between the incoming gas being liquefied and the evaporating liquid that is undergoing rectification.

Another object is to provide an apparatus and method for obtaining gases of high purity, at reduced cost for installation and attendance.

Another object is to provide a rectifying column with a high pressure direct heating means, which is susceptible to close temperature regulation and which comprises an efficient separator in compact form.

Other objects will be in part obvious and in part pointed out hereinafter.

The invention accordingly comprises the features of construction and operation, combinations of elements, arrangements of parts and sequences of steps which are exemplified in the structure hereinafter described and the scope of the application of which will be indicated in the following claims.

In the accompanying drawings, in which is shown one of various possible embodiments of this invention,

Figure 1 is a sectional elevation of a preferred form of rectifying column, with some of the auxiliary apparatus; and

Figure 2 is a transverse section on the line 2—2 of Figure 1.

Similar reference characters indicate similar parts throughout both views of the drawings.

The present invention, generally speaking, relates to an improved apparatus and method for low-temperature work, and particularly for obtaining oxygen and nitrogen from air by liquefaction and subsequent rectification, the heat energy required for distillation being obtained primarily by transfer of heat from the gas undergoing liquefaction at a higher pressure. Other features, such as the employment of a high-pressure direct heating device and the provision of automatic means for maintaining at a proper value the pressure in the heating device, will be clear from the following description.

Referring now to the accompanying drawings, there is illustrated a rectifying column, preferably in the form of a vertical cylinder 21 whose external connections comprise an intake pipe 22 for the pre-cooled, purified and partly expanded incoming air; a delivery pipe 24 for the nitrogen or other low-boiling constituents; and a delivery pipe 26 for the oxygen or other high-boiling constituents. The structural features of the invention, as well as the functions of the various parts and the sequence and purpose of the several steps of the process, will probably be most readily understood by considering the path of the fluid from the time the air is first utilized at room temperature and atmospheric pressure until the nitrogen and oxygen, again at normal temperature, are conveyed through measuring devices and stored in suitable receptacles.

Of the ten stages which comprise the preferred form of the process of the present invention, the first, second, third, fourth and tenth are omitted from the drawings. The ten stages may be listed somewhat categorically as follows: first, compressing; second, pre-cooling; third, purifying; fourth, cooling in a temperature interchanger; fifth, cooling by expansion; sixth, scrubbing; seventh, liquefying; eighth, cooling by pressure release; ninth, heating and rectification of the constituents, and tenth, heating of the separate gases evolved during the ninth stage. Obviously, many of these stages may

be omitted, or replaced by other operations, without departing from the scope of the invention.

During the first stage, air at room temperature and atmospheric pressure is compressed. This causes a rise of temperature.

In the second stage, the compressed air is passed through a preliminary cooling device, where it resumes normal temperature and preferably is cooled to a temperature somewhat below normal, but is maintained at the pressure attained in the first stage.

In the third stage the air is purified by suitable means known in the art.

In the fourth stage, this cooled compressed and purified air has its temperature further lowered by being passed through a heat-interchanging device, preferably of the type illustrated, described and claimed in my co-pending application, Serial No. 125,534, filed October 14, 1916, for apparatus and method for transferring heat. At the end of the fourth stage, the air is delivered in an upward direction through the pipe 27, as indicated by the arrow 3, Figure 1.

From the pipe 27 the cooled and compressed air passes upwardly through the fifth stage, as indicated by the arrow 5, through the expansion valve 29, controlled by the hand wheel 30 through the valve stem 32, a suitable heat-insulating sleeve 33 being provided to prevent conduction of heat from the packing box 35 to the air passing through the valve. It is of course to be understood in this connection that this type of expansion device is merely illustrative and that other and more efficient expansion means may be used if desired. In this stage, the air is cooled to the point of liquefaction and is preferably partly liquefied, to an extent sufficient so that the latent heat of evaporation of the liquefied portion may approximately equal the heat gains in succeeding parts of the apparatus.

From the valve 29 the air passes through its sixth stage, which has been referred to as scrubbing. The air first travels upwardly, as indicated by the arrow 6^a, through the intake pipe 22, to a point adjacent the upper end of the column 21, whence it is directed downwardly by a cap 36, as indicated by the arrows 6^b, through a long vertical cylinder 38 surrounding the intake pipe 22. Within this cylinder 38 is scrubbing material comprising preferably beads 39 of graduated size larger on top and diminishing in size toward the bottom of the cylinder. The cylinder with its contents thus acts as a separator in which frost particles and other solid impurities are removed from the air and retained until a convenient time for cleaning the apparatus. The air travels downwardly, as indicated

by the arrows 6^c, until it reaches the bottom of the cylinder 38, and is then divided into a plurality of streams for the seventh stage of the process.

For the seventh stage, the cold and purified air, still under pressure, is divided into a plurality of streams traveling substantially radially outward through the distributing pipes 41, as indicated by the arrows 7^a, whence it is delivered to the several sets of heat-interchanging coils 42, through which the air travels in a generally upward direction to the collecting ring 44 adjacent the top of the rectifying column 21. From the latter ring, the stream of air passes through the pipe 45. In order that the several streams of air may travel through approximately the same distance in their passage upwardly from the distributing pipes 41 to the collecting ring 44, the length of the several coils 42 is made approximately equal. This may be done by making the coils of larger diameter of greater pitch than the coils of smaller diameter; and in order further to subdivide the air into streams and to make the most efficient use of the available space, the coils of larger diameter and of greater pitch are wound in multiple sets so that there will be more individual coils of a given larger diameter than there are coils of a given smaller diameter. Thus, for example, the innermost coil, or the coil of smallest diameter, consists of a single coil having a given pitch while the coil of the next larger diameter may be wound with a greater pitch and may be duplicated so as to bear a relation to the first or inner coil similar to the relation between a double thread and a single thread. In this manner all the individual coils or convolutions may be made to have approximately the same total length and may furthermore be made to have the same rise in a vertical direction per foot of travel therethrough of the streams of air. This feature of construction provides a uniform flow of fluid through each coil and results in a substantially uniform heat distribution. Packed around and between the coils 42, are beads or particles 46 of copper or other material having a high thermal conductivity. This structure, as described and claimed per se in my co-pending application, Serial No. 125,534, above mentioned, accelerates the transfer of heat between the fluid within the coils and the fluid outside the coils, first by breaking up the outer fluid into a large number of minute streams, all in intimate thermal contact with the beads or particles 46, and second, by providing, through contacting beads, a series of paths of low thermal resistance between the container for the first fluid and all portions of the second or outer fluid. Suitable packing (not shown)

is provided around the outside of the cylinder 21 to protect the fluids from external losses. As above noted, this compactness with a corresponding reduction of superficial area is of the highest value as the greatest losses incurred in this entire process are due to the inward leakage of heat which is roughly proportional, other things being equal, to the total external or superficial area. Aside from this loss, the process is carried on substantially by an interchange of energy without the necessity for drawing upon an external source. It may also be noted at this point that the method by which 10 the fluid is passed downwardly in this apparatus with a consequent breaking up into numerous minute streams, not only conduces to an efficient and effective heat interchange but thoroughly intermingles all portions of 20 the fluid and accelerates the interchange of constituents of rectification. This breaking up of the streams with the above effects applies not only to the descending liquid but to the ascending gases, and both are in intimate thermal contact with the beads 46.

In order to minimize or prevent the travel of heat energy lengthwise or vertically of the column 41, horizontal layers of heat-insulating beads or particles 47, such as coke, 30 clinkers, charcoal, and the like, broken up into particles of suitable size, may be arranged at intervals vertically of the column. These beads 47 of low thermal conductivity in no wise detract from the rapid conduction of heat in a generally horizontal direction, but by insulating adjacent vertical portions of the column from one another, the beads 47 divide the column into what may be termed a plurality of horizontal 40 thermal layers, and make it possible to maintain at different heights of the column progressively increasing or decreasing temperatures. In this way the temperature best suited for one operation, such as the evaporation 45 of a high percentage of the low-boiling constituent, may be maintained at and near the top of the column, while another temperature best adapted for another operation, such as the evaporation of a high 50 percentage of the high-boiling constituent, may be maintained at and near the bottom of the column, without in any way impairing the effectiveness or rate of heat transfer between fluids in any of the thermal layers 55 of the column.

The rectifying column is thus provided with a large number of heating coils 42, affording a large surface for the rapid conduction of heat to the fluid undergoing rectification, and the effective heating surface is further increased by the beads 46, each of which is in intimate contact with the fluid to be evaporated. And this intimate 60 relation between the fluids and the heating 65 surface makes possible an accurate control

of the temperature throughout the column by regulating the pressure in the seventh stage, hereinafter described.

The cold air passing upwardly through the coils 42, as indicated by the arrows 7^b, is progressively liquefied by coming into intimate thermal contact with progressively colder fluid that is traveling in a downward direction outside the coils, and this causes the upwardly traveling fluid to be liquefied, 70 the liquefaction becoming complete by the time the fluid reaches the collecting ring 44, where it is forced into the pipe 45, as indicated by the arrow 7^c. There is sufficient velocity to the upwardly traveling fluid so 75 that the liquefied particles thereof are readily carried along toward the pipe 45 over the slightly ascending pitch of the coils 42. The latent heat yielded during liquefaction 80 of the fluid is readily absorbed by the fluid traveling downwardly in the spaces outside and between the coils 42. This second fluid, as will be hereinafter described, is the liquefied air undergoing progressive rectification 85 during the ninth stage of the process. The 90 seventh stage is completed when the liquefied air reaches the pipe 45.

During the eighth stage, the liquid air, delivered under some pressure through the pipe 45, is forced through the expansion 95 valve 50, as indicated by the arrow 8, whence it flows downwardly for the ninth stage, hereinafter described, as shown by the arrow 9^a. The reduction of pressure during 100 the eighth stage and accompanying lowering of boiling point causes a partial evaporation 105 of nitrogen together with a small percentage of oxygen and absorption of latent heat, which causes a cooling of the portion 110 of the fluid that remains in a liquid condition.

One object of this invention is to have the pressure and boiling point during liquefaction accurately maintained at a value 115 higher than the pressure and boiling point during evaporation which takes place at approximately atmospheric pressure. With this arrangement, it becomes possible to evaporate accurately at a lower temperature than the temperature of the liquefaction, 120 and thus the latent heat required for evaporation may be obtained by simply transferring to the evaporating fluid the latent heat given up at the higher temperature by 125 the fluid that is being liquefied at the higher pressure. Accurate evaporation results under proper conditions to give the desired result rather than an undesirable result. Thus, for example, conditions as to temperature, pressure, rate of flow and such factors, must be in the proper relation to each other to result in evaporation at the proper and desired rate and to result also in the 130 production of a product of a purity requisite for commercial success. By the means

provided by this invention, the pressure and hence the boiling points during liquefaction are accurately maintained at a value higher than the pressure and hence boiling points existent during evaporation. The evaporation takes place preferably at approximately atmospheric pressure. It thus becomes possible to rectify the fluid constituents of the varying composition in the ninth stage hereinafter described, in direct thermal contact with the constituents of liquefaction in the seventh stage and at temperatures best suited for efficient rectification. The maintenance of proper temperatures, particularly during rectification, is a matter of great moment. The descending liquid undergoing rectification in the ninth stage, to be hereinafter described, retains the maximum amount of high boiling constituents, and carries them well toward the base of the rectifying column, while the ascending vapors undergoing rectification in this ninth stage retain and carry the maximum amount of low boiling constituents well toward the top of the column. It is thus possible to rectify efficiently, (in the ninth stage) at a lower temperature than the temperature of liquefaction (in the seventh stage) and the latent heat required for rectification is obtained by transferring directly to the fluids in the ninth stage the latent heat given up by the fluids in the seventh stage. In this way, both liquefaction and evaporation may be effected with a high degree of precision. The liquefaction above mentioned occurs during the seventh stage. The evaporation is effected in the ninth stage, hereinafter described.

In order to make the apparatus automatic in its operation, the expansion valve 50 is provided with a heat-insulating sleeve 52 connected to a pressure-regulating device 54. The latter is preferably of the spring-loaded diaphragm type and is so constructed that the liquid (from the seventh stage) which communicates through sleeve 52, exerts its pressure upon the bottom of the diaphragm 53, raising the diaphragm to open the valve slightly through stem 55, as the pressure exceeds a predetermined amount, and lowering the diaphragm to move the valve 50 toward its closed position if the pressure falls below normal. And since the valve communicates directly with the bottom of the diaphragm 53, without intervening packing, a free movement of the valve stem and consequent accurate pressure regulation is attained. The regulator 54 is maintained as nearly as possible at normal temperature conditions since the sleeve 52 is substantially non-conductive of heat as above described, and since the active fluid passing through the sleeve and acting upon the diaphragm 53 is mainly gaseous and is acted upon by the pressure

of the liquid in the system with which the sleeve 52 is in connection. A tube 57 communicates with a gage 58 to indicate the pressure prevailing in the seventh stage of the apparatus. The hand wheel 60 serves for the adjustment of the regulator 54, so that the standard of pressure maintained may be under manual control.

From the eighth stage, the cooled and partly evaporated liquid flows downwardly, as indicated by the arrow 9^a, to the distributing head 62, whence the fluid is divided into a plurality of divergent streams passing outwardly through the distributing pipes 63, as indicated by the arrows 9^b, whence the fluid travels in a generally downward direction through the spaces between and outside the coils 42 containing the upwardly traveling fluid of the seventh stage. The ninth stage comprises the downward travel of the liquid and may be considered as divided into a large number of sub-stages, representing evaporation and rectification of progressively higher ratios of oxygen to nitrogen in progressively lower situated thermal layers of the rectifying column 21; during the first sub-stage, at the uppermost thermal layer of the column, the conditions of temperature and pressure are maintained at such a value that evaporation of a portion of the low-boiling constituent, such as nitrogen, takes place, together with a minimum percentage of oxygen or other high-boiling constituent, the remainder of the nitrogen and oxygen remaining in liquid form until it reaches the next sub-stage of the process, at the next lower thermal layer of the rectifying column, where the evaporation and rectification is maintained at a slightly higher ratio of oxygen to nitrogen.

In progressively lower thermal layers of the column, the temperature standard is progressively higher owing to the fact that the descending liquid absorbs heat from the walls of the tubes 42 which are of course at a relatively higher temperature throughout. And as a consequence, the percentage of oxygen increases toward the bottom of the column. The evaporated oxygen travels upwardly to the adjacent thermal layers, where it is checked by rectification because of the lower heat standards maintained and lower percentage of oxygen maintained at the upper thermal layers. So that the gas rising upwardly from the uppermost thermal layer has a fairly constant oxygen content, equal to the minimum value maintained in the rectifier. This gas travels upwardly, as indicated by the arrows N, through the vapor scrubber 65, and thence outwardly through the delivery pipe 24. The scrubber 65 serves to separate from the gas the small entrained vapor particles or mist of liquid air, which are carried off by the boiling gas. The gas is caused to travel in a generally downward

direction through the scrubber, and thence upwardly, while the liquid particles gravitate toward the funnel-shaped bottom 66 and re-enter the rectifying column through the liquid seal 67. The scrubbing material preferably comprises small beads 69 carried on a screen 70. The gas, mainly nitrogen, that is delivered to the pipe 28 is at the low pressure prevailing in the ninth stage and its 10 temperature is that of the boiling point of the liquid as it issues in the valve 50 at the pressure prevailing at that point. In this condition, the cold nitrogen gas is used in a temperature interchanger (not shown) during the tenth stage for the purpose of cooling the incoming air, and at the same time raising the temperature of the outgoing gas, as hereinafter described.

In the lower thermal layers of the ninth 20 stage of the apparatus, the descending liquid, mainly oxygen, is further heated by the ascending air within the coils 42 (seventh stage) to approximately the boiling point of oxygen for the prevailing low pressure in this ninth stage. At this temperature, the nitrogen has of course been practically all rectified and evaporated. The oxygen is now partly or entirely evaporated, the latent heat needed for this purpose being taken 25 from the ascending liquefying gas within the coils 42 (seventh stage) which as above described liquefies at a higher temperature than the evaporating temperature for the oxygen because of the higher pressure prevailing in the seventh stage. The oxygen gas, which may be partly liquid, is taken off through the lower delivery pipe 26, as indicated by the arrow O, whence it passes to the tenth stage. A feature of this process which should be especially noted is the effective and thorough interchange of latent 35 as well as sensible heat. The amount of heat absorbed in evaporation and given off in liquefaction is of a high value and corresponding importance, and it is to be noted here that this heat, as well as the sensible heat, is efficiently interchanged between the various fluids throughout the process. For example, the latent heat required to evaporate 40 the nitrogen when the liquid nitrogen has reached its boiling temperature, is absorbed from the gaseous air and represents to a large extent the latent heat which must be extracted from the latter to permit its 45 liquefaction.

It might at this point be noted that the automatic valve 50 in maintaining automatically a constant pressure on the fluid during the seventh stage serves to control 50 automatically the temperature limits between which the rectification as hereinbefore described takes place and to maintain also automatically a proper and desired distribution of temperature between these limits.

For most efficient operation the temperature 55 distribution should be such that the temperature at the top of the rectifying column corresponds substantially to that of the boiling point of the low boiling constituent, namely the nitrogen, and such that the temperature at the bottom of the rectifying column corresponds substantially to that of the boiling point of the high boiling constituent, namely oxygen. The intervening zones in the rectifying column, in which during the 60 ninth stage hereinbefore described the progressive evaporation and rectification takes place, are thus by the maintenance of the temperature limits maintained at temperatures intermediate of these limits so that the plurality of sub-stages of the ninth stage 65 take place throughout a uniform temperature gradient automatically maintained.

As hereinbefore described, there takes place in the various zones in the rectifying column during the ninth stage simultaneous partial evaporation and partial condensation; that is, the descending liquid constantly undergoes partial evaporation while the resultant vapors which rise therefrom and are moved in an upward direction constantly undergo partial condensation. The liquid resulting from this partial condensation is again partially evaporated after reaching a lower, warmer zone in the column and these steps are repeated throughout the various zones of the rectifying column, provided these zones are maintained at the requisite temperatures as above described. For efficient rectification therefore it is highly desirable to maintain the necessary temperature gradient within the rectifying column. To determine one of the temperature limits, for example that existing at the bottom or warmer region of the rectifying column, the fluid is introduced into the distributing pipes 41 to the coils 42 preferably in vapor form so that the corresponding temperature in the rectifying column at the lower region may correspond substantially to the boiling point of the oxygen or constituent of higher boiling point of the fluid thus introduced and at the pressure prevailing in the coils, and which at the upper region in the rectifying column corresponds substantially to the temperature of the nitrogen or constituent of lower boiling point of the liquefied fluid discharged into the rectifying column and at the pressure prevailing therein. The intermediate regions in the rectifying column will assume temperatures intermediate of these two limits and will thus represent a predetermined temperature gradient in passing from the coldest to the warmest regions in the rectifying column.

From these considerations it may further be noted that should, for example, the pressure of the fluid entering the coils 42 at the

base thereof be greater than that corresponding to the boiling point of the oxygen or the high boiling constituent of the fluid, the temperature limit at the base of the rectifying column will be correspondingly too high and the function of the lower rectifying zones in the column will be detrimentally affected. Moreover, the higher pressure in the coils 42 as thus assumed will cause an unduly rapid condensation of the fluid in the lower portions of the coils 42 and will thus permit the fluid therein to leave these lower portions in liquid form rather than partial liquid form. As the flow of the thus liquefied fluid continues upwardly through the coils 42 under the above-assumed conditions, the fluid in the coils 42 will thus be deprived of the necessary latent heat required to supply efficiently the liquid traveling downward in the rectifying column with the necessary heat of vaporization. Hence evaporation in the upper regions of the rectifying column fails to take place and the liquid in the rectifying column must therefore penetrate the lower zones of the rectifying column in order to receive the necessary heat of vaporization and in so doing act further to lower the temperature in the lower portions of the coils 42.

Assuming now that the pressure during the seventh stage, or in other words the pressure of the fluid undergoing liquefaction in the coils 42, is maintained below that at which its temperature corresponds to that of the boiling point of oxygen or of the constituent of higher boiling point, the temperature in the lower regions of the rectifying column will be maintained correspondingly too low and a reversal of the detrimental effects above set forth will take place. Hence, efficient rectification in the rectifying column may be seriously impaired by undesirable effects which tend to disturb the temperature limits between which the rectifying column is intended to operate and to disturb also the temperature gradient existing between these two limits.

In providing the automatic valve 50, however, for maintaining automatically a constant pressure during the seventh stage or during the stage at which the fluid in the heat interchanging coils 42 is undergoing liquefaction, the temperature limit at the lower regions of the rectifying column is automatically maintained constant and the pressure is preferably maintained at such value that this limit will correspond to the boiling point of the oxygen or constituent of high boiling point of the fluid. This boiling point is of course dependent upon the pressure prevailing in the rectifying column and hence it will be seen that the automatic valve 50 after being once set serves automatically, with a given pressure exist-

ing in the rectifying column, to maintain 65 the proper relation between the pressure in the heat interchanging coils 42 and the pressure in the rectifying column which, as hereinbefore noted, is preferably atmospheric pressure. The automatic valve therefore 70 controls automatically the distribution of liquefaction of the fluid uniformly throughout the coils 42; and hence, as will be readily seen from the foregoing considerations of assumed abnormal conditions, controls 75 automatically the uniform distribution of the latent heat of liquefaction throughout the coils available for the uniform and progressive rectification and evaporation of the constituents that take place in the rectifying 80 column. The automatic valve thus serves to preserve a temperature gradient throughout the rectifying column and insures a highly efficient action of rectification in the rectifying 85 column.

In the tenth stage, the cold nitrogen gas with small oxygen content and the cold oxygen gas from the ninth stage, are conveyed in separate channels through the heat-interchanger above described in connection 90 with the fourth stage. In this interchanger, the products of rectification absorb heat from the incoming air, and thus cool the entering fluid (fourth stage). The gaseous products are ultimately led off through a flow-regulating device and meter serving to adjust their rate of flow, a feature which, in connection with the automatic pressure regulation, gives an absolute control over the purity of the products.

From the above, it will be clear that with the apparatus and process herein provided, the several objects of the invention are realized and other advantageous results obtained.

As various possible embodiments might be made of the above invention and as various changes might be made in the embodiments above set forth, it is to be understood that all matter herein set forth or shown in 110 the accompanying drawings is to be interpreted as illustrative and not in a limiting sense.

Having thus revealed my invention, I claim and desire to secure by Letters Patent 115 of the United States:

1. The method of rectifying gases which consists in liquefying a gaseous fluid by causing a transfer of heat therefrom to finely divided particles of high heat conductivity maintained at progressively lower heat standards, expanding the liquefied fluid, evaporating and rectifying the expanded fluid by passing it over progressively warmer sections of said particles of high heat conductivity, the heat yielded to said particles by said incoming gaseous fluid during liquefaction being transferred to the 120 125

expanded liquefied fluid to evaporate and rectify the latter.

2. The method of rectifying gases which comprises liquefying a gaseous fluid by passing it in a plurality of subdivided streams through finely divided particles of high heat conductivity maintained at progressively lower heat standards, whereby heat is transferred from said fluid to said particles, expanding the liquefied fluid, and evaporating and rectifying the expanded fluid by passing it over progressively warmer sections of said particles of high heat conductivity, the heat yielded to said particles by said incoming gaseous fluid being transferred to the expanded liquefied fluid to evaporate and rectify the latter and to liquefy the gaseous fluid.

20 3. The method of separating fluids which comprises partially liquefying a gaseous fluid by expansion, passing the partially liquefied fluid in a plurality of subdivided streams through a heat transferring device to extract heat therefrom to complete the liquefaction thereof, subjecting the liquefied fluid to evaporation and rectification by passing said liquefied fluid in reverse direction and in a plurality of subdivided streams through progressively warmer portions of said heat transferring device to withdraw heat from said subdivided fluid undergoing liquefaction to complete the liquefaction thereof, and maintaining constant automatically the pressure of the fluid undergoing complete liquefaction.

4. The method of separating fluids which comprises partially liquefying a gaseous fluid by expansion, completing the liquefaction thereof by passing said partially liquefied fluid through a heat transferring device maintained at progressively lower heat standards, subjecting the liquefied fluid to evaporation and rectification by passing it through progressively warmer portions of said device to withdraw heat from said fluid undergoing liquefaction to complete the liquefaction thereof, and maintaining automatically the temperature limits between the highest heat standard and the lowest heat standard in said device.

5. The method of separating fluids which comprises subdividing a fluid into a plurality of separate streams and passing said separate streams of fluid through substantially equal distances and each at substantially the same rise per foot of travel through successively colder portions of a heat transferring device to liquefy it, subdividing the liquefied fluid into a plurality of small streams, and evaporating and rectifying the fluid by passing said small streams through progressively warmer portions of said device whereby the evaporating fluid obtains its latent heat of evaporation from

the latent heat of liquefaction of the incoming fluid in said plurality of separate streams, and separating the progressively evaporated constituents.

6. The method of rectifying fluids, which comprises cooling a fluid, expanding the fluid, passing the fluid through successively colder portions of a heat-transferring device to liquefy the fluid, maintaining constant automatically the pressure of the fluid during liquefaction, to maintain the temperature limits between which said device operates substantially constant, rectifying the fluid and heating the constituents of rectification by causing them to absorb heat from the initial fluid which is being cooled.

7. The method of handling fluids which comprises partially liquefying a gaseous fluid by expansion, scrubbing or cleansing the partially liquefied fluid to remove solid particles therefrom, and completing the liquefaction of said fluid by subjecting it to thermo-contact with progressively colder portions of a heat transferring device.

8. The method of handling gases which comprises cooling a gas, partially liquefying the gas by expansion, scrubbing or cleansing the partially liquefied gas to remove solid particles therefrom, completing the liquefaction of the gas by subjecting it to progressively colder portions of a heat transferring device, evaporating and rectifying the liquefied gas through successively warmer portions of said device by causing the evaporating gas to absorb its latent heat of evaporation from the latent heat of liquefaction of the incoming gas, and maintaining constant automatically the pressure during the liquefaction of said gas.

9. The method of handling fluids, which comprises cooling a gaseous fluid under pressure, reducing the pressure to reduce the temperature, scrubbing or cleansing the fluid to remove solid particles therefrom, and liquefying the fluid by subjecting it to thermal contact with progressively colder portions of a heat-transferring device.

10. The method of handling fluids, which comprises cooling a gaseous fluid under pressure, reducing the pressure to reduce the temperature, scrubbing or cleansing the fluid to remove solid particles therefrom, and liquefying the fluid by subjecting it to progressively colder portions of a heat-transferring device and rectifying the fluid at a pressure automatically maintained constant.

11. The method of rectifying a fluid having a high boiling and a low boiling constituent which consists in expanding the fluid, passing the fluid through successively colder portions of a heat-transferring device to liquefy the fluid, maintaining automatically a range of temperature in said

device varying progressively from substantially the boiling point of the low boiling constituent to substantially the boiling point of the high boiling constituent, passing the 5 liquefied fluid through successively warmer portions of said device thereby to cause said liquefied fluid to absorb its latent heat of evaporation from the latent heat of liquefaction of the incoming fluid under- 10 going liquefaction whereby the low boiling constituent is evaporated first and withdrawn and the high boiling constituent is evaporated later in warmer portions of said device and withdrawn separately from said 15 first constituent.

12. The method of handling fluids, which comprises cooling a gaseous fluid in a heat-transferring device, liquefying the fluid in a second heat-transferring device, maintaining 20 constant automatically the temperature limits between which said second device operates, lowering the pressure of the fluid to reduce its boiling point and evaporating and rectifying at progressively higher heat 25 standards the several constituents of the fluid by passing the fluid through said second device in reverse direction to the incoming fluid, and heating one of the products of separation by heat transferred from 30 the entering fluid in said first device.

13. The method of separating fluids which consists in liquefying a gaseous fluid by passing it through successively colder portions of a heat transferring device, preventing interchange of heat between adjacent portions of said fluid, respectively, in said 35 successively colder portions of said heat transferring device by insulating said portions from one another, expanding the fluid 40 to reduce the boiling points of its several constituents, and evaporating and rectifying the fluid through progressively warmer insulated portions of said device by causing the evaporating fluid to obtain its latent 45 heat of evaporation from the latent heat of liquefaction of the incoming fluid, and separating the progressively evaporated constituents.

14. The method of handling fluids, which 50 comprises compressing a gaseous fluid, cooling the compressed fluid in a heat-transferring device, expanding the cooled fluid, cleansing or scrubbing the fluid, liquefying the purified fluid by passing it through 55 successively colder portions of a second heat-transferring device, reducing the pressure of the liquefied fluid through a valve operated automatically to maintain at constant 60 pressure the fluid on the high pressure side of the valve, passing the fluid in the opposite direction through said second device to effect evaporation and rectification at progressively higher temperatures in different parts of said second device, separating 65 the constituents of rectification, and

passing said constituents through said first device to heat said constituents and simultaneously cool the incoming fluid therein.

15. The method of separating air into oxygen and nitrogen, which comprises compressing the air cooling the compressed air in a heat-transferring device, expanding the cooled air, cleansing or scrubbing the air, liquefying the purified air by passing it through successively colder portions of a second heat-transferring device, reducing the pressure of the liquefied air through a valve operated automatically to maintain at constant pressure the air on the high-pressure side of the valve, passing the air 75 in the opposite direction through said second device to effect evaporation and rectification at progressively higher temperatures in different parts of said second device, separating the nitrogen and oxygen thus evolved, and passing said nitrogen and oxygen in separate channels through said first device to heat said nitrogen and oxygen and simultaneously to cool the incoming air 80 therein.

16. In apparatus of the class described, in combination, a heat-transferring device comprising successive portions maintained at progressively increasing heat standards, insulating means interposed between adjacent portions of said device for preventing heat interchange between said adjacent portions, and means for passing through said device a liquefied fluid, and for evaporating and rectifying in successive portions of the device the several constituents of progressively higher boiling point.

17. In apparatus of the class described, in combination, a heat-transferring device comprising successive portions maintained at 105 progressively increasing temperatures, insulating means interposed between adjacent portions of said device for preventing heat interchange between said adjacent portions, means for passing through said device a liquefied fluid, and for evaporating and rectifying, in said successive insulated portions of the device, the several constituents of progressively higher boiling point, and means for withdrawing separately the several 110 constituents.

18. In apparatus of the class described, in combination, a heat transferring device for the passage therethrough of a liquefied fluid, means for imparting heat to said fluid to evaporate it, a separating device adapted to remove entrained, non-gaseous matter from said fluid after evaporation, means for conducting said evaporated fluid through said device, and separate conducting means constituting a liquid seal for returning entrained non-gaseous matter from said device to said evaporating fluid.

19. In apparatus of the class described, in combination, expansion means for cooling a 120

gaseous fluid, a cleansing device comprising beads of progressively smaller size, means for passing the expanded fluid through said device, and a heat-transferring device for 5 liquefying the purified fluid.

20. In apparatus of the class described, in combination, expansion means for cooling a gaseous fluid, a cleansing device comprising beads of progressively smaller size, means 10 for passing the expanded fluid through said device to remove solid particles therefrom, and a heat-transferring device for liquefying the purified fluid, said device comprising portions maintained at progressively 15 lower heat standards, whereby a gradual and a complete liquefaction is effected.

21. In apparatus of the class described, in combination, a heat-transferring device for cooling a gaseous fluid, means for cleansing 20 the fluid, a second heat-transferring device for liquefying the fluid, means for passing a liquefied fluid of lower boiling point than the first fluid through said second device in opposite direction to the flow of the first 25 fluid to evaporate and rectify a constituent of the second fluid, a cleansing device, and means for withdrawing the evaporated constituent through said cleansing device.

22. In apparatus of the class described, in combination, a heat-transferring device for cooling a gaseous fluid, means for cleansing the fluid, a second heat-transferring device for liquefying the fluid, the latter device comprising progressively colder portions, 30 means for passing a liquefied fluid of lower boiling point than the first fluid through said second device in opposite direction to the flow of the first fluid to evaporate a constituent of the second fluid, a cleansing device comprising beads or particles, and a supporting screen therefor, and a liquid seal for returning entrained fluid to said second fluid, and means for withdrawing the evaporated constituent through said cleansing device. 35

23. In apparatus of the class described, in combination, means for liquefying a fluid, an expansion device for reducing the pressure thereof after liquefaction, means for 40 automatically regulating the pressure during liquefaction, means for evaporating and rectifying the fluid at progressively higher heat standards by absorbing heat from progressively warmer portions of the incoming 45 fluid being liquefied, and means for withdrawing separately the evolved constituents.

24. In apparatus of the class described, in combination, coils adapted for the passage therethrough of a fluid, a container surrounding the coils and providing a channel for the passage of a second fluid within the container and outside the coils and in thermal contact with the coils and said first fluid, means for insulating the coils and 50 container in a plurality of thermal layers, 55

and means within said container for purifying the fluid.

25. In apparatus of the class described, in combination, coils adapted for the passage therethrough of a fluid, a container 70 surrounding the coils and providing a channel for the passage of a second fluid within the container and outside the coils and in thermal contact with the coils and said first fluid, means for insulating the coils 75 and container in a plurality of thermal layers, and means within said container for purifying the fluid prior to its passage through said coils, said means comprising beads or particles arranged in the path of 80 said fluid and of progressively smaller size.

26. In apparatus of the class described, in combination, a heat-transferring device for liquefying a gaseous fluid, heat insulating means subdividing said device into a plurality of successive portions for preventing heat interchange between adjacent portions and for maintaining said portions at progressively lower heat standards, means for expanding the liquefied fluid, and means for 85 subjecting the fluid to progressive distillation and rectification of its several constituents by passing said fluid through portions of said device of successively higher heat standards, the heat yielded by the incoming fluid during liquefaction being transferred to the expanded fluid to evaporate 90 the latter.

27. In apparatus of the class described, in combination, means for compressing a gaseous fluid, a heat-transferring device for cooling the compressed fluid, means for expanding the cooled fluid, means for cleansing or scrubbing the fluid to remove solid particles, a second heat-transferring device for 100 liquefying the purified fluid, the latter device comprising portions maintained at progressively lower heat standards, means for reducing the pressure of the liquefied fluid, said last-named means being operated automatically to regulate the pressure of the fluid on the high-pressure side thereof, means for passing the fluid through said second heat-transferring device in the opposite direction to the incoming fluid to 105 effect evaporation and rectification at progressively higher temperatures in said second device, means for separating and purifying the products of distillation, and means for passing said products through said first heat-transferring device to heat said products and simultaneously cool the incoming 110 fluid therein.

28. Apparatus for separating air into oxygen and nitrogen, comprising means for compressing the air, a heat-transferring device for cooling the compressed air, means for expanding the cooled air, means for cleansing or scrubbing the air to remove 125 solid particles, a heat transferring device 130

for liquefying the purified air, said latter device comprising portions maintained at progressively lower heat standards, a valve for reducing the pressure of the liquefied air, means for passing the air through said second heat-transferring device in the opposite direction to the incoming fluid to effect evaporation and rectification at progressively higher temperatures in different parts of said second device, said valve being operated automatically to regulate the pressure of the liquefying air, means for separating the products of rectification, and means for passing said products through said first heat-transferring device to heat said products and simultaneously cool the incoming air therein.

29. The method of separating fluids, which comprises sub-dividing a fluid into a plurality of separate streams and passing such sub-divided fluid through successively colder portions of a heat transferring device to liquefy it, preventing interchange of heat between the portions of said fluid respectively in adjacent portions of said fluid successively colder portions of said heat transferring device by insulating said portions from one another, expanding the fluid to reduce the boiling points of its several constituents, sub-dividing said expanded fluid into a plurality of small streams, and evaporating and rectifying the fluid through progressively warmer portions of said device by causing the evaporating fluid to obtain its latent heat of evaporation from the latent heat of liquefaction of the incoming fluid, and separating the progressively evaporated constituents.

30. The method of separating fluids, which comprises sub-dividing a fluid into a plurality of separate streams and passing each of said separate streams through substantially equal distances through successively colder portions of a heat transferring device to liquefy it, preventing interchange of heat between the portions of said fluid respectively in adjacent portions of said fluid successively colder portions of said heat transferring device by insulating said portions from one another, expanding the fluid to reduce the boiling points of its several constituents, breaking the fluid up into a plurality of minute streams by means of particles of high thermal-conductivity, and evaporating and rectifying the fluid at progressively higher temperatures by passing the fluid through said device in thermal contact with said particles by causing the evaporating fluid to obtain its latent heat of evaporation from the latent heat of liquefaction of the incoming fluid, and separating the progressively evaporated constituents.

31. The method of separating fluids,

which comprises passing a fluid through successively colder portions of a heat transferring device to liquefy it, expanding the fluid to reduce the boiling points of its several constituents, sub-dividing the fluid into a plurality of minute streams by means of particles of high thermal-conductivity forming part of said device, and evaporating and rectifying the fluid at progressively higher temperatures by passing the fluid through said device in contact with said particles in turn in thermal contact with the incoming fluid, and separating the several evaporated constituents.

32. In apparatus of the class described, in combination, a plurality of concentric coils for a fluid arranged in multiple and of varying diameters so that said coils are arranged one within the other, the coils of a diameter greater than the innermost coil being wound in multiple sets to provide substantially the same length for all the coils and to provide substantially the same rise per foot of travel therethrough of said fluid, a container surrounding the coils and providing a channel for the passage of a second fluid outside of said coils and within the container, and means including particles of high thermal conductivity disposed within said container and about said coils for breaking up said second fluid into a large number of small streams and for affording intimate thermal contact between the two fluids.

33. In apparatus of the class described, in combination, a plurality of concentric coils for a fluid arranged in multiple and of varying diameters so that said coils are arranged one within the other, the coils of a diameter greater than the innermost coil being wound in multiple sets to provide substantially the same length for all the coils and to provide substantially the same rise per foot of travel therethrough of said fluid, a container surrounding the coils and providing a channel for the passage of a second fluid outside of said coils and within the container, means including particles of high thermal conductivity within said container and about said coils and disposed in a plurality of layers spaced along the axis of said coils for breaking up said second fluid into a large number of small streams and for insuring intimate thermal conductivity in a direction substantially transversely of the axis of said coils, and means of low thermal conductivity interposed between adjacent layers of said particles of high thermal conductivity for preventing the flow of heat between adjacent layers.

In testimony whereof, I have signed my name to this specification this first day of November, 1916.

RUDOLPH VUILLEUMIER.
